ABSTRACT: A combination piezoelectric transducer and diaphragm including a thin circular disc of polarized piezoelectric ceramic material stressed into a dish-shaped configuration and confined in that configuration by a metal ring attached to the edge of the disc. A conductive metal layer is formed on each of the major surfaces of the disc to form a pair of electrodes for the disc, so that the application of electrical signals to the electrodes causes the disc to operate in an expander mode, thereby producing movement of the center of the disc in a direction perpendicular to the major surfaces thereof. Movement of the center of the disc in a perpendicular direction to the major surfaces thereof causes a corresponding electrical signal to be generated across the electrodes.

PRESTRESSED PIEZOELECTRIC AUDIO TRANSDUCER

BACKGROUND OF THE INVENTION

In the use of a piezoelectric transducer as the driving element for an air-loaded diaphragm, it generally is the practice to utilize a separate diaphragm driven by the piezoelectric element. To achieve maximum mechanical movement with a predetermined electrical signal, Bimorph multilayer piezoelectric polycrystalline ceramics operating in a bender mode generally are employed to drive the diaphragm. It is desirable to directly use the mechanical movement of the piezoelectric transducer as a diaphragm, but this has not proved feasible for coupling acoustic signals to air since conventional piezoelectric Bimorph crystals cannot be made thin enough to provide the proper impedance matching with air loading.

SUMMARY OF THE INVENTION

Accordingly it is an object of this invention to provide an improved piezoelectric transducer device.

It is another object of this invention to provide a piezoelectric transducer which also operates directly as a diaphragm coupled to air.

It is an additional object of this invention to use a thin prestressed slab of piezoelectric material as a combination electrical to mechanical transducer and diaphragm operable at audio frequencies and coupled to air.

In accordance with a preferred embodiment of this invention a single thin slab of piezoelectric material, capable of operating in an expander mode, is placed under stress and polarized. The slab is clamped in the stressed configuration by attaching it in an opening in a frame corresponding to the shape of the slab, and electrodes are placed on the opposite major surfaces of the slab for the application of electrical impulses to and the obtaining of electrical signals from the slab. The frame is relatively rigid in the plane of the opening but is capable of torsional movement about an axis in the frame parallel to the plane of the opening.

BRIEF DESCRIPTION OF THE DRAWING

FIG. 1 is a drawing illustrating the method of making a piezoelectric transducer/diaphragm in accordance with a preferred embodiment of this invention;

FIG. 2 is a perspective view of the completed diaphragm made in accordance with FIG. 1;

FIGS. 3 and 4 are partially cutaway side views illustrating operation of the piezoelectric transducer/diaphragm made in accordance with the method illustrated in FIG. 1;

FIG. 5 is a top view of the diaphragm shown in FIGS. 2, 3 and 4 used to explain the operation of the diaphragm;

FIG. 6 is a partially cutaway side view of a device useful in explaining the operation of the diaphragm;

FIG. 7 shows typical response curves used to determine the proper parameters of the transducer/diaphragm; and

FIG. 8 is a detailed partial sectional view of another embodiment of the invention.

DETAILED DESCRIPTION

Referring now to FIG. 1, there is illustrated, in partially cutaway side view, a method for making a combination piezoelectric transducer/diaphragm. A circular piezoelectric disc 10 made of a suitable polycrystalline material, such as barium titanate, is coated with conductive layers on both of the major surfaces to form electrodes 11 and 12, which may be applied to the disc or slab 10 in any suitable manner, such as by plating, sputtering or painting. The diameter of the disc 10 is substantially greater than the thickness of the disc, although in FIG. 1, the relative dimensions have been exaggerated in order to show more clearly the elements of the transducer.

The disc 10 with the electrode coatings 11 and 12 then is placed in a groove in a ring 13 preferably made out of material

having a high Young's modulus of elasticity. The groove or cutaway portion of the ring is defined by a vertical surface 14 and a lower surface 15, with the disc 10 resting on the lower surface 15 and being distorted by the application of a weight indicated by the arrow applied approximately at the center of the disc. This causes the disc to assume the dish-shaped configuration shown in FIG. 1 and to rest on the lower surfaces 15, with the edge of the disc 10 being within the confines of the diameter across the ring 13 between the surfaces 14.

When the disc 10 is in the position shown in FIG. 1, with the weight applied to its center, a DC polarizing potential may be applied to the electrodes 11 and 12, causing a unidirectional (DC) electrical field to be established between the electrodes 11 and 12 and, therefore, through the ceramic disc 10. This DC field should be sufficiently high to cause a polarization of the ceramic disc 10 to be effected. If the deforming pressure and the electrical field is applied at normal room temperature, it generally is necessary to use a relatively high potential and to maintain the deformation and potential for several hours. Alternatively, heat may be applied to the disc to raise its temperature above the Curie point before the DC potential is applied, and then the heat is removed, permitting the disc to cool through the Curie point, while the pressure and electrical field are maintained. If polarization of the ceramic disc 10 is accomplished by this latter method, a lower polarizing electrical field and a shorter time length generally can be employed.

While the disc 10 is distorted by the weight and has the electrical field applied to it, the edges of the disc 10 are cemented by a suitable cement, such as an epoxy cement, into the groove formed by the surfaces 14 and 15 on the metallic ring 13; and the epoxy cement is allowed to set. After the epoxy has set, the weight and DC polarizing field are removed. The epoxy forms a rigid bond between the edge of the disc 10 and the ring, so that the disc is held in the distorted dish-shaped configuration which it attained under the action of the weight applied to it. The resultant transducer/diaphragm is shown in FIG. 2.

The piezoelectric diaphragm assembly shown in FIGS. 1 and 2 may be coupled directly to air; because the single layer polycrystalline ceramic piezoelectric disc 10 may be made thin enough, thereby having a low enough impedance, to provide a sufficient impedance match to air that audio frequency vibrations may be directly coupled to and from the disc using amplifiers of the type normally employed in small radios, telephones and the like.

Before entering into a discussion of the operation of the transducer/diaphragm assembly shown in FIGS. 1 and 2, refer to FIG. 6 which illustrates an idealized configuration of the assembly useful in explaining the principles of operation of the device. The device shown in FIG. 6 is substantially the same as the device shown in FIGS. 1 and 2, but employs a different ring configuration in the form of a ring 23, having a cross-sectional configuration such that the inner surface of the ring forms a circular knife edge which is clearly shown in the cross-sectional view of FIG. 6. The piezoelectric slab or disc 10 then is prestressed into a dished configuration and is wedged into the opening in the ring 23, with the knife edge engaging the edge of the disc 10 substantially at the midpoint of the thickness of the disc all around its circumference. As a result, the disc 10 is constrained against movement along any diameter because of the rigid nature of the material of the ring 23.

The application of an alternating current from a current generator 20 causes an alternating field to be applied across the disc 10 by means of the electrodes 11 and 12. In the presence of an alternating field, the disc alternately expands and contracts along its diameters. Since the disc 10, however, is constrained against movement in the direction of its diameters, this expansion and contraction is translated into a movement normal or perpendicular to the general plane of the disc 10, as indicated by the vertical double ended arrow in FIG. 6. As the disc 10 expands, the amount of the dishing of the disc increases, causing a downward movement of the center of the disc 10 as seen in FIG. 6. Similarly, as the disc contracts along

its diameters, the amount of dishing decreases, causing an upward movement of the center of the disc 10 as viewed in FIG. 6.

Because the amount of the "dishing" of the disc varies in accordance with the signals applied to the electrodes 11 and 12 there is relatively friction-free rotation or a hinging of the disc at the knife edge contact point along the edge of the disc 10. The embodiment shown in FIG. 6, however, is difficult to attain as a practical matter due to the difficulty of placing and holding the disc 10 in place on the knife edge of the ring 23, and also due to the extremely large pressures exerted on the disc 10 by the line contact of the knife edge. As a consequence, the compromise configuration shown in the FIGS. 1, 2, 3, and 4 of the drawing proves to be the most practical from an actual operating standpoint.

In order most closely to duplicate the operation of the embodiment shown in FIG. 6, it is desirable that the ring 13 used in the assembly previously described in conjunction with FIGS. 1 and 2 be made of a material having a high Young's modulus, providing a high torsional elasticity, but also providing a maximum rigidity to the expansion and contraction of the disc 10 along its diameter. Materials out of which the ring 13 may be fabricated and which exhibit these desired characteristics are tungsten, tungsten carbide, alumina ceramics, molybdenum and the like. The range of Young's modulus of these materials extends from approximately 320-1000 $\times 10^6$ p.s.i. (pounds per square inch) at room temperature. The cross-sectional diameter of the ring preferably should be small to provide the desired torsional characteristics and should be large to provide maximum resistance to expansion and contraction of the disc 10 in the plane of the ring 13. It has been found that by making the cross-sectional diameter of the ring 13 approximately twice the thickness of the disc 10 (for a disc 4.7 mils thick and 2-inches diameter), a good compromise can be reached.

Referring now to FIGS. 3, 4 and 5, the operation of the device shown in FIGS. 1 and 2 illustrated. When an alternating current signal of a first polarity from the source 20 is applied to the electrodes 11 and 12, the piezoelectric disc 10 expands as indicated by the arrows placed underneath the disc 10 in FIG. 3. As illustrated in FIG. 5, the disc 10 expands along every diameter thereof. Since the ring 13 is chosen to have sufficient rigidity to prevent expansion of the disc 10 in the plane of the ring 13, the expansion of the disc 10 is translated into a downward motion as indicated by the arrow above the disc 10 in FIG. 3, causing the disc to be dished further or deeper than the configuration it attains when no signals are present from the source 20. The downward movement or dishing of the disc 10 causes the edge of the disc to pivot inwardly at the upper surface of the disc, and the modulus of elasticity of the material forming the ring 13 permits a torsional rotation of the ring 13 about a circular axis passing through the center of the circle formed by each cross section of the ring all around the ring 13. This rotation is indicated by the arrows to the left and right of the ring 13 in FIG. 3. The torsional rotation of the ring 13 functions to approximate the ideal hinge condition provided by the knife edge configuration of the apparatus shown in FIG. 6.

On the opposite half-cycles of the alternating signal obtained from the source 20, the material of the disc 10 contracts along every diameter thereof as seen in FIG. 5 and as illustrated by the arrows beneath the disc 10 in FIG. 4, causing the center of the disc 10 to move upwardly, as indicated by the arrow above the disc 10 in FIG. 4, which in turn causes the edge of the disc 10 to rotate in the opposite direction. The ring 13 then undergoes torsional rotation in the opposite direction about the axis thereof, as indicated by the arrows on the left and right sides of the ring 13 in FIG. 4.

This expansion and contraction of the disc 10 is repeated for every cycle of the signal obtained from the source 20, causing the bow or dishing of the disc 10 to alternately increase and decrease in the direction of the vertical arrows shown in FIGS. 3 and 4. This movement of the disc drives the

air loading the disc to produce sounds at the driving frequencies of the AC signal source 20. It can be seen that in order to provide the operation described, the cement attaching the disc 10 to the ring 13 must provide a rigid bond.

If the material of the ring 13 did not provide the torsional elasticity described but if the ring 13 were rigid in response to torsional forces, the hinging action which has been described would not occur, and distorted bending of the disc 10 at its edge would result in high mechanical losses, substantially reducing the efficiency of the device. The diameter of the disc 10 is chosen to be relatively large compared to the thickness, so that a high transformation ratio is attained, since a relatively small radial movement of the disc 10 provides a high axial movement at the center of the disc.

Referring now to FIG. 7, there is shown a chart of response curves which are used in order to determine the proper impedance matching of the transducer/diaphragm assembly shown to the air loading the disc 10. One means by which the proper impedance matching may be determined is to provide a fixed energy input to a number of different samples of assemblies, varying one parameter of the assemblies at a time and measuring the audio output frequency response for each of the different assemblies being tested. For example, assume that a given diameter of the disc 10 and a given material and configuration for the ring 13 are provided for a number of different samples, each having a different thickness of the disc 10. The audio frequency inputs then are applied in a similar manner to each of the samples, with the audio output response curves for each of the samples being measured.

If the disc 10 is too thick, a response curve such as the curve A is obtained, tending to provide a high audio response or a peak at a particular frequency and to provide highly attenuated audio responses over the remainder of the frequency range in which it is desired to utilize the transducer/diaphragm assembly. On the other hand, if the disc 10 is too thin, thereby causing too great a compliance of the disc 10, a frequency response curve such as curve C is observed, providing a relatively flat audio response characteristic, but too highly attenuated to be useful. When approximate matching of the impedance of the disc 10 to the air loading the transducer is obtained, a curve such as curve B is observed with a relatively flat and high audio output for all of the frequency range desired. This type of experimentation may be used, individually varying different parameters of the transducer/diaphragm assembly in order to determine the desired materials and dimensions for matching the impedance of the transducer/diaphragm to the air loading the diaphragm. Other techniques may be utilized to attain this impedance matching, but the above technique has been found successful in producing properly matched assemblies.

Since the diameter of the disc 10 is relatively large compared to the thickness of the disc 10, the piezoelectric ceramic material may be subject to fracturing under some conditions of operation. In order to substantially eliminate or to minimize the tendencies for the thin piezoelectric material in the disc 10 to fracture, a thin layer of plastic material, such as Mylar, is cemented to one or both surfaces of the disc 10. FIG. 8 illustrates a partial cross section of the disc 10 with the electrodes 11 and 12 deposited thereon and further including a layer of Mylar over the electrode 12. The Mylar layer 16 could be placed directly on the disc 10 with the electrode 12 placed over the Mylar layer if so desired. In the operation of discs having such a Mylar layer, it has been found that substantially no fractures occur, thereby resulting in greatly improved mechanical characteristics of the assembly. In a typical assembly, the ceramic material of the disc 10 may be of the order of 4.7 mils in thickness, with the Mylar layer being 0.25 mils thick.

In the operation of the transducer/diaphragm described above, a relatively wide band of response over the audio frequency range has been obtained. In order further to improve the frequency range of the transducer/diaphragm, it may be desirable to replace one or both of the electrodes 11

and 12 with a resistive conductive coating. In order to improve the low frequency response of the device, it also may be desirable to attach a lightweight conical diaphragm, such as a paper cone, to the disc 10 substantially at the center point thereof, although in most applications such an additional paper diaphragm should not be necessary.

In an actual design of the transducer/diaphragm shown in FIGS. 1, 2, 3, 4, and 5, the following materials and dimensions were used:

TABLE I

Ring 13 material.....	Tungsten
Ring 13 inside diameter.....	1.910"
Ring 13 cross sectional diameter.....	.080"
Disc 10 material.....	Clevite PZT5H or Honeywell C27
Disc 10 undistorted diameter.....	2.000"
Disc 10 thickness.....	.004"
Disc 10 pre-stressed dishing (center).....	Approx. .030"
Assembly frequency response.....	IKC-20KC
Input power.....	20mw

The above values are given, however, only by way of illustration and are not to be construed as limiting the scope of the present invention in any manner.

I claim:

1. A piezoelectric transducer including in combination: frame means defining an opening having predetermined dimensions thereacross, the frame means having an axis therein in a plane substantially parallel to the plane of the opening and being relatively rigid in the plane of the opening to maintain said predetermined dimensions, and the frame means being capable of torsional movement about the axis;

a thin slab of piezoelectric ceramic material operable in an expander mode and of a shape generally conforming to the opening in the frame means, the ceramic slab being bent to an extent less than its elastic limit along at least one major dimension thereof, with the edges thereof fitting in the opening in the frame means;

a conductive layer on at least a portion of each of the opposing major surfaces of the slab of piezoelectric material to form a pair of opposing electrodes on the slab; and means for attaching the slab to the frame means in the opening.

2. The combination according to claim 1 wherein the frame means is made of a material having a Young's modulus of elasticity greater than 310×10^5 p.s.i.

3. The combination according to claim 2 wherein the frame is a ring having a groove therein and wherein the piezoelectric

slab is a disc, the edge of which is placed in the groove.

4. The combination according to claim 3 wherein the piezoelectric disc is stressed into a dished shape, the arc of the dish determining the step-up ratio of the diaphragm transducer.

5. The combination according to claim 2 wherein the material of the frame is selected from the group comprising: tungsten carbide, tungsten, alumina ceramics, and molybdenum.

10 6. The combination according to claim 1 further including a thin layer of plastic material bonded to and substantially covering at least one of the major opposing surfaces of the slab, the thickness of the plastic material being substantially less than the thickness of the slab.

15 7. The combination according to claim 6 wherein the layer of plastic material is a layer of Mylar.

8. A piezoelectric transducer/diaphragm operating at audio frequencies and coupling directly to air including in combination:

20 a prestressed dish-shaped piezoelectric circular disc operable in an expander mode and the diameter of which is substantially greater than the thickness thereof; a rigid relatively nonexpansive ring, having an axis having an inner diameter sufficient to maintain the piezoelectric disc in the dish-shaped configuration with a predetermined bow therein, the ring being capable of torsional movement about the axis thereof; means for rigidly attaching the edge of the piezoelectric disc to the inner surface of the ring; and electrodes on at least a portion of the opposing major surfaces of the ceramic disc for applying electrical signals to and obtaining electrical signals from the disc, the disc forming the sole diaphragm for the transducer.

35 9. The combination according to claim 8 wherein the ring has a groove therein and wherein the edge of the piezoelectric disc is placed in the groove.

10 10. The combination according to claim 9 wherein the ring is made of a material having a Young's modulus of elasticity greater than 310×10^5 p.s.i.

11. The combination according to claim 10 wherein the material of the ring is selected from the group consisting of: tungsten, alumina ceramics, molybdenum, tungsten carbide.

12. The combination according to claim 8 further including a Mylar layer attached to and substantially covering at least one of the major surfaces of the ceramic disc, the thickness of the Mylar layer being substantially less than the thickness of the disc.
